UNITED STATES PATENT OFFICE.

ALBERT KLAIBER, OF RIDGEWOOD, NEW YORK.

MEDICAL APPARATUS FOR THE TREATMENT OF THE INTESTINES.

Application filed April 12, 1926. Serial No. 101,297.

This invention relates to improvements in medical apparatus employed for the subaqueous irrigation of the intestines, and has particular reference to a saddle construction of the type disclosed and claimed in my co-pending application filed September 4, 1924, Serial No. 735,743.

Briefly, there is shown in the above identified application, a saddle upon which a patient is seated during treatment and which is provided therein with a discharge opening. Projecting from this opening and carried by a feed tube supported by the saddle is an anal tube through which a medicament is fed into the intestines. It becomes desirable, in practice, to subject patients to treatments of different characters such as intra-rectal and intra-sphincteric subaqueous baths. For the former bath, a long anal tube is required which will extend through the sphincter canal to the rectum ampulla and which can be used for loosening or softening the scybala and for acting upon the intestines with medicinal solutions. When applying the intra-sphincteric treatment, the anal tube should be short so as not to reach the rectum ampulla but only discharge within the narrow sphincter canal.

With the apparatus of said application it becomes necessary, before performing the different treatments above mentioned, to change the anal tube for a shorter or longer one and sometimes such changes are necessary, due to variations in the body conformations of patients, after a patient is seated upon the saddle and the treatment has been started. In the latter event, the patient must arise while the change of tubes is being effected and thereafter reseat himself upon the saddle.

An object of the present invention is to overcome the necessity of changing the anal tube for each different treatment and, to this end, there is provided a construction wherein a single anal tube is employed which may be adjusted longitudinally so that it may be extended different distances into the anus.

Another object is to so mount the anal tube that the same will have pivotal movements and be yieldably supported relative to the feed tube whereby the anal tube will always have a tendency to assume a position in longitudinal alignment with the feed tube.

The above and other objects will appear more clearly from the following detailed description, when taken in connection with the

accompanying drawing, which illustrates a preferred embodiment of the inventive idea.

In the drawing—

Figure 1 is a vertical longitudinal section through the saddle constructed in accordance with the invention;

Figure 2 is a transverse section on the line 2—2 of Figure 1; and

Figure 3 is an enlarged longitudinal section showing the details of the mounting for the anal tube.

The apparatus of the present invention is used in the same manner as described in the aforesaid application and is shown as comprising a saddle including a body portion 5 made of any suitable material and arcuately shaped in longitudinal section so as to form a convenient seat for the patient. The saddle is maintained in an inclined position and at its rear or lower portion carries upon its under surface and adjacent its side edges two supports 6 made of rubber or other desired material which will engage the bottom of a tub and aid in preventing slipping of the saddle. At a point slightly forward of the supports 6 the body portion 5 has secured to the underside thereof and extending forwardly therefrom a supporting leg 7 the free end of which is provided with a cushion or pad 8 which also engages the bottom of the tub to support the saddle in proper position.

At a point slightly forward of the center of the body portion the same is provided with a discharge opening 9. A discharge duct 10 extends in an inclined position from the underside of the body portion and has one end aligned with the opening 9 so as to receive waste therefrom and convey the same to a suitable drain or receptacle such as described in the aforementioned application.

The duct is supported by a brace 10^a connected to the forward end of the leg 7. In order to further insure the proper discharge of the emitted contents of the intestines through the discharge duct, a ring or collar 11 is mounted in the opening 9 and extends into the adjacent end of the duct 10. The outer end of said ring is bent to form a flange 12 utilized to retain in position on the body portion a pad or air cushion 13 which surrounds the opening 9. The pad has an air tube 14 by means of which the same may be inflated after the patient is seated upon the saddle.

Rings 15 are provided at the ends of the saddle to which suitable straps (not shown)

may be attached for suspending the saddle from the body of the patient and retaining the same in proper position relative to said body.

5 When a treatment is concluded, the duct 10 may be flushed out and the patient cleaned by the injection of a flow of water through a pipe 16 extending into the duct with the inner end of the pipe adjacent the opening 9.

10 The lower portion of the duct 10 adjacent the inner end thereof is provided with a diagonally depending bearing member 17 in which is slidably mounted a medicament feed tube 18. The lower or outer end of 15 said tube has an enlarged portion 19 to which is connected a branch tube 20 capable of connection to a suitable source of medicament supply. The portion 19 is provided with laterally extending pins 21 engageable in the 20 slotted lower ends of the arms 22 forming a part of an operating lever 23. The upper ends of said arms 22 are bent to embrace the duct 10 and are pivotally connected thereto at 24. From this construction it will be 25 seen that when the lever 23 is swung about the pivots 24, the feed tube 18 and its branch 20 may be adjusted as indicated by the dotted lines in Figure 1, with the tube 18 sliding longitudinally in the bearing 17.

30 The inner end of the tube 18 is internally screw threaded to receive the threaded portion 25 of a coupling member 26 having a passage 27 therethrough which extends in alignment with said tube. An enlarged 35 head 28 is formed on the coupling and is utilized to position the same on the tube and detach it therefrom. Said head also forms a stop which engages the inner end of the bearing 17 to limit the outward movement of the tube 18. The end of the coupling opposite the portion 25 is enlarged to provide a ball member 29 which fits into a socket portion 30 at the inner end of an anal tube 31, a ring 32 having screw threaded engagement with said portion 30 retaining said tube 31 in connection with the coupling 26. In this manner a universal joint connection is formed between the feed and anal tubes which will permit of the latter having 40 pivotal movements relative to the former, thus facilitating the entry and proper positioning of the anal tube in the sphincter canal and rectum ampulla. Then by operating the lever 23 it will be apparent that 45 the tube 31 may be adjusted in a longitudinal direction to vary its effective length.

50 Means are provided for yieldably supporting the tube 31 so that the same will have a tendency to, at all times, assume a position in direct longitudinal alignment with the feed tube 18 and at substantial right angles to the plane of the opening 9. This is done to prevent, as much as possible, contact of the free end of the tube 31 with the walls of the sphincter canal and rectum ampulla as

the tube is being inserted and thus avoid unnecessary irritation of the organs of the patient. Said means is preferably in the form of a coil spring 33 interposed between the head 28 and ring 32 and soldered or otherwise secured to the latter. Said spring will thus normally maintain the tubes 18 and 31 in alignment but will permit of any necessary pivotal movements of the latter tube.

55 Should it be desired to remove the tube 18 from its bearing 17 for purposes of cleaning or sterilizing the parts, the coupling 26 together with the tube 31 may be first detached by unthreading the coupling from the tube 18 whereupon said tube may be withdrawn outwardly by manipulating the lever 23 after which the pins 21 can be disengaged from the slotted lower ends of the arms 22.

What is claimed is:

1. In a medical apparatus of the class described, a saddle including a body portion having a discharge opening, a feed tube, an anal tube connected to said feed tube and projecting through said opening, means for adjusting said feed and anal tubes in a longitudinal direction to vary the effective length of the latter tube, and means for yieldably supporting said anal tube in longitudinal alignment with said feed tube.

2. In a medical apparatus of the class described, a saddle including a body portion having a discharge opening, a feed tube, an anal tube projecting from said opening and having a pivotal connection with said feed tube, means for adjusting said tubes to vary the effective length of the anal tube, and means for yieldably supporting said anal tube in longitudinal alignment with said feed tube.

3. In a medical apparatus of the class described, a saddle including a body portion having a discharge opening, a duct extending from said opening, a feed tube supported by said duct and movable relative thereto toward and away from said opening, an anal tube connected to said feed tube and having its effective length varied by the movements of said feed tube, and means carried by said duct and connected to said feed tube for moving the same.

4. In a medical apparatus of the class described, a saddle including a body portion having a discharge opening, a duct extending from said opening, a feed tube supported by said duct and movable relative thereto toward and away from said opening, an anal tube connected to said feed tube and having its effective length varied by the movements of said feed tube, and a lever having pivotal connection with said duct and with said feed tube and operable to move the latter relative to said duct.

5. In a medical apparatus of the class described, a saddle including a body portion having a discharge opening, a duct extend-

ing from said opening, a feed tube supported by said duct and movable relative thereto toward and away from said opening, an anal tube having a pivotal connection with said feed tube and adapted to have its effective length varied by the movements of the latter tube, and a lever having pivotal connection with said duct and with said feed tube and operable to move the latter relative to said duct.

6. In a medical apparatus of the class described, a saddle including a body portion having a discharge opening, a duct extending from said opening, a feed tube supported by said duct and movable relative thereto toward and away from said opening, an anal tube having a pivotal connection with said feed tube and adapted to have its effective length varied by the movements of the latter tube, and means for yieldably supporting said anal tube in longitudinal alignment with said feed tube.

7. In a medical apparatus of the class described, a saddle including a body portion having a discharge opening, a duct extending from said opening, a feed tube supported by said duct and movable relative thereto toward and away from said opening, an anal tube having a pivotal connection with said feed tube and adapted to have its effective length varied by the movements of the latter tube, means for yieldably supporting said anal tube in longitudinal alignment with said feed tube, and a lever having pivotal connection with said

duct and with said feed tube and operable to move the latter relative to said duct.

8. In a medical apparatus of the class described, a saddle including a body portion having a discharge opening, a feed tube supported by said body adjacent said opening and movable toward and away therefrom, an anal tube connected to said feed tube, and means connected to a portion of said body and to said feed tube for moving the same and said anal tube.

9. In a medical apparatus of the class described, a saddle including a body portion having a discharge opening, a feed tube arranged adjacent said opening, a coupling carried by said feed tube, an anal tube having pivotal engagement with said coupling, and means carried by said coupling for yieldably supporting said anal tube in longitudinal alignment with said feed tube.

10. In a medical apparatus of the class described, a saddle including a body portion having a discharge opening, a feed tube adjacent said opening, an anal tube projecting from said opening, ball and socket members carried by said tubes to permit of a universal movement of the anal tube relative to the feed tube, and means engageable with one of said members for yieldably supporting said tubes in longitudinal alignment with each other.

In testimony whereof I have affixed my signature.

ALBERT KLAIBER.
